UNITED STATES PATENT OFFICE

THOMAS O. SCHRADER, OF ALLENTOWN, PENNSYLVANIA, ASSIGNOR TO THE DENT HARDWARE COMPANY, OF FULLERTON, PENNSYLVANIA, A CORPORATION OF PENNSYLVANIA

BRACKET

Application filed July 9, 1931. Serial No. 549,771.

This invention relates to brackets, particularly of the kind utilized to support shelves in refrigerators, show cases and the like.

Heretofore, it has been customary to provide three types of supporting brackets, made necessary by the desirability of providing stops to limit endwise movement of the shelf or supported structure, when it extends over a plurality of brackets. In order to accomplish this result a right-hand end bracket having a stop or stops located to limit the movement of the shelf at the right-hand side of the bracket arm was used. Similarly, a left-hand bracket was provided including a stop located in the left-hand side of the bracket to limit the movement of the shelf thereon. In addition, to the specially shaped end brackets, a center bracket was required that included no stops whatever so that the shelf could extend completely across the supporting surface of the bracket arm. It was, accordingly, necessary to manufacture and maintain a stock of the three kinds of brackets in order to furnish the necessary brackets to properly support a shelf or the like, and at the same time provide means to limit its movement in both endwise directions.

This invention aims to provide a bracket designed so that the same bracket may be used effectively as a right-hand end, a left-hand end or a center bracket.

A further object of the invention is to provide a bracket for supporting a shelf in which the bracket arm is provided with a pair of readily removable stops, either one or both of which may be removed in order to adapt it to serve effectively to support an elongated shelf and to limit its endwise movement in either direction.

A still further object of the invention is to provide a bracket for supporting shelves of any character in which the bracket arm is provided with laterally spaced stops in the form of pins that are removably mounted in the bracket provided to receive them,

which pins may all be removed, or certain of them may be maintained in position, thus serving their stop function, which arrangement provides a neat-appearing, simple construction effectively serving any one of three purposes; namely, as a center bracket, a right-hand end bracket or a left-hand end bracket.

Still further objects of the invention will appear as a description thereof proceeds with reference to the accompanying drawing in which:

Figure 1 is a plan view of an elongated shelf supported by three brackets constituting an essential part of the present invention, the superfluous stops thereof being removed.

Figure 2 is an elevational view of the bracket of the present invention.

Figure 3 is a plan view of the bracket illustrated in Figure 2.

Figure 4 is a detail view showing one of the stop pins in side elevation.

Figure 5 is a section taken on the plane indicated by the line 5—5 in Figure 3.

Like reference characters indicate like parts throughout the several figures.

The bracket of the present invention is designed particularly to support elongated shelves and to limit the endwise movement of said shelves in both directions. Such shelves are used in refrigerators, show cases or the like, and in order that the brackets may serve the purpose of limiting the endwise movement it is essential that they be provided with stops that are disposed at the proper side of the bracket. This has heretofore necessitated a special left-hand end bracket, a special right-hand end bracket and a center bracket, over which the shelf extended completely, and which, accordingly, required no stops. In order that a single bracket may serve the three purposes just referred to by removal of extremely simple stops, a bracket of a single form is disclosed that can be used suc-

cessfully to serve as a right-hand end, a left-hand end or a center bracket.

Preferably, the bracket that may be interchangeably used in any one of the positions noted consists of a supporting arm 10 preferably integrally formed with a bracket securing portion 11 provided with an integral lug 12 designed to enter an opening in the supporting structure, and a perforation 13 provided to receive the shank of a suitable fastener extending therethrough and through an aligned opening in the supporting structure.

Preferably the arm 10 and the securing portion 11 are connected together by an integral brace 14 of any approved form. As shown, said brace may be straight or it may be ornamented in any desired way. Preferably, the arm 10, the securing portion 11 and the brace 14 are formed of relatively narrow width, and these portions of the bracket may be of uniform width as illustrated, or they may assume any other desired relative thicknesses. The end of the arm 10 remote from the portion 11 is provided with a stop 15 in the form of a lug projecting upwardly from and laterally of the arm 10. Said stop is, as illustrated in Figure 3, of a length exceeding the width of the arm 10 so as to contact with the shelf supported on the bracket over a relatively wide area so that said shelf may be maintained firmly from movement in a direction along the length of the bracket. Said stop may, however, be made of any desired length. The height of the stop 15 is preferably equal to the thickness of the shelf that is to be supported thereon. The bracket so far described may assume any form, since no part so far described constitutes a part of the present invention.

In order to provide the bracket with a relatively wide shelf supporting surface the arm 10 is, preferably, recessed as indicated at 16 and 17 and shelf supports 18 and 19 are preferably secured in, and snugly fit said recesses. Rivets 20, or any other securing means may be used, or said supports may be formed integrally with the bracket arm. As indicated in Figure 3, the shelf supports 18 and 19 provide a bearing surface extending substantially laterally in both directions of the arm 10.

Each of the supports 18 and 19 are provided with a pair of laterally spaced openings 21 and 22, the walls of which are preferably threaded. Stops that are, preferably, in the form of pins 23, of substantially uniform diameter and cross-sectional area from end to end, are provided for detachable association with said supports in the openings 21 or 22 therein. In order to conveniently and fixedly secure the stop pins 23, the ends thereof intended for reception in the openings 21 or 22 are threaded as shown at 24, though any

other convenient way of holding said pins in the openings may be employed.

The bracket is provided in its completed form with stop pins 23 removably mounted in each of the openings 21 and 22 of the bracket supports 18 and 19 and when so equipped, the bracket is capable of being used as a center bracket, a right-hand end or a left-hand end bracket by simply removing all or either the right-hand or the left-hand pins forming a part thereof.

The bracket just described is used in the way clearly illustrated in Figure 1, in which brackets 25, 26 and 27 are utilized to support a shelf 28, which may be of glass or any other suitable material, in a refrigerator, show case or the like. Said brackets are attached to a supporting wall 29 of any form by means of bolts 30, 31 and 32 entering the openings 13 in each of said brackets, and by causing the lugs 12 of each of said brackets to enter matching recesses in the supporting wall or structure. In the bracket 25, which is a left-hand end bracket the right-hand pins 23 are removed from the openings 21 while in the bracket 27 which is a right-hand end bracket the left-hand pins 23 are removed from the openings 22 in the bracket support. The center bracket 26 has all of its pins removed from the openings 21 and 22 so that the shelf 28 may rest firmly on the shelf supports 18 and 19.

It will thus be seen that by the removal of a few readily removable inexpensive pins, the simple bracket of the present invention may be readily converted into a right-hand end, a left-hand end or a center bracket. The removable stops may assume any other convenient form, other than pins, though the latter is preferred, because of the simplicity of the construction, and the ease with which pins may be applied and removed.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. A shelf supporting bracket adapted for use as a right-hand, left-hand or center bracket comprising a bracket arm provided with means to facilitate its attachment to a support, and a pair of stops removably secured to lateral extensions of said arm in substantially spaced relation in a direction transverse to the length of said arm, whereby said bracket may be used as a center bracket by removal of both stops, as a right-hand bracket

by removal of the left-hand stop so that the right-hand end of a shelf may be firmly supported by said extensions and abut against the remaining stop, and as a left-hand bracket by removal of the right-hand stop so that the left-hand end of a shelf may be firmly supported by said extension and abut against the remaining stop.

2. The bracket defined in claim 1 in which said stops constitute pins designed for removable insertion in openings of said extensions.

In testimony whereof I affix my signature.
THOMAS O. SCHRADER.
